Sigmund Herzog
ATTORNEY

UNITED STATES PATENT OFFICE.

SAMUEL SPITZ, OF NEW YORK, N. Y.

TOILET ARTICLE.

Application filed May 8, 1928. Serial No. 276,116.

The present invention relates to toilet articles, and more particularly to one of the toothbrush type.

One of the objects of the invention is to provide a toothbrush in which the bristles are mounted upon a head, which may be removed at will, for the purpose of replacement or sterilizing, from the handle member, and to pivotally mount upon the said handle member a gum massaging implement that is adapted to be conveniently extended to operative position and to be folded in relation to said handle when it is not to be used.

A further object of the invention is to provide a novel means for holding the brush head in position upon the handle, and which will permit of ready removal of the said head from and of convenient mounting thereof on said handle.

20 A further object of the invention is to provide a simple locking means for maintaining the massaging implement both in its extended and folded positions in relation to the handle of the brush.

25 A still further object of the invention is to provide a toilet article of the character described which is simple in construction, durable in use, and which is thoroughly practical commercially.

30 With these and other objects in view, which will more fully appear as the nature of the invention is better understood, the same consists in the combination, arrangement and construction of parts hereinafter described,

35 pointed out in the appended claims and illustrated in the accompanying drawings, it being understood that many changes may be made in the size and proportion of the several parts and details of construction within

40 the scope of the appended claims, without departing from the spirit or sacrificing any of the advantages of the invention.

Two of the many possible embodiments of the invention are illustrated in the accompanying drawings, in which:—

Figure 1 is a side elevation of a toilet article constructed in accordance with the present invention; Fig. 2 is a top plan view thereof; Fig. 3 is a bottom plan view of the same; Fig. 4 is a section taken on line 4—4 of Fig. 1; Fig. 5 is a side view of a portion of the device illustrating the mounting of the brush

head on the handle portion; Fig. 6 is a top plan view of a brush head adapted to replace the head shown in Figs. 1 and 2 of the drawings; Fig. 7 is a side elevation of the brush head shown in Fig. 6; Fig. 8 is an end view thereof; Fig. 9 is a view similar to the one shown in Fig. 1 of a portion of a modified device; Fig. 10 is a top plan view of the modification shown in Fig. 9 with the brush head removed; and Fig. 11 is an end view of the brush head shown in Fig. 9.

Referring now first to Figs. 1 to 4, inclusive, of the drawings, the numeral 12 designates the handle of the brush, which may be made of any suitable material but should be of such nature as to be resilient when thin. In order to increase the resiliency of the handle, its central portion 13 may be somewhat slender, for a purpose hereinafter to be described. In one of the end portions of the handle is provided a transverse recess 14, extending throughout the width of the said portion. The front and end walls 15 and 16 of the said recess are substantially V-shaped and formed as to incline inward into the recess, each forming a slight overhang for engaging the brush head and to retain the latter in place. In other words, the said front and rear walls are undercut in opposite directions.

The brush head comprises a back 17, to which are attached in any suitable manner bristles 18. The transverse sides 19 and 20 of this back conform in configuration to that of the front and rear walls 15 and 16, respectively, of the recess 14 in the handle 12 of the brush, the back being adapted to fit snugly into and entirely fill the recess in the handle. As appears from Fig. 2 of the drawings, the said transverse sides of the back are substantially V-shaped in configuration and beveled to fit the inclines of the front and rear walls of the recess in the brush handle, so that, when introduced into the recess in a manner hereinafter to be described, the overhangs on the transverse walls of the recess 14 firmly keep the brush head against movement perpendicularly to the bottom of the recess, while the V-shape of the said walls, in co-operation with the V-shaped transverse sides of the brush head, prevent movement of the latter transversely of the said handle.

To the opposite end of the handle is fastened by means of a pivot 21' a bar-shaped support 21, carrying upon its free end a resilient block 22, which is provided with resilient massage projections 23. On the underface of the bar-shaped support are provided two lugs 24, the same being arranged in the longitudinal axis of the said support, one on each side of the pivot 21'. These lugs are adapted to co-operate with two sockets 25 in the juxtaposed face 26 of the handle 12. Preferably, the said sockets are transversely V-shaped, and the lugs are similarly shaped to snugly fit into the said sockets.

15 In alignment with the recess 14 there are provided in the sides of the handle two notches 12', to permit the user to take hold of the brush head when the latter is to be removed from the handle.

20 When the brush head is to be removed from the handle for replacement or for sterilizing, the user takes hold of the handle in the manner indicated in Fig. 5 of the drawings, depressing the slender central portion 13 thereof, whereby the rear wall 16 of the recess in the handle is disengaged from the transverse side 20 of the brush back so that the latter may be easily removed from the recess. Of course, in mounting a brush head on the handle, the central portion thereof is bent downwards as shown in Fig. 5 of the drawings, whereby the front transverse side 19 of the said head may be conveniently engaged with the front transverse wall 15 of the recess, 35 after which the handle is permitted to swing back into its normal position shown in Fig. 1 of the drawings, whereby the rear transverse wall of the said recess will engage the transverse side 20 of the brush head. The latter is thus firmly held in operative position 40 upon the handle.

The resilient block 22, with its resilient massage projections 23, is adapted to be used for massaging the gums so as to maintain the same in good condition. When this massaging implement is to be used, it is swung 180° around its pivot 21' from the position shown in Fig. 1 of the drawings. The co-operating lugs 24 and sockets 25, forming part of the support 21 and handle 12, respectively, maintain the massaging implement both in its extended and folded positions.

55 A brush head above described may be replaced, with the head 27 illustrated in Figs. 6 to 8, inclusive, of the drawings. This head comprises a back 28 of a configuration corresponding exactly to that of the back 17 above described. This back is provided with an elevation 29, in which are mounted bristles 30, the latter being radially disposed on the said elevation and serve for cleaning the interstices between the teeth.

60 In Figs. 9 to 11, inclusive, a modified toothbrush is illustrated, differing from the one above described mainly in that the trans-

verse front and rear walls 31 and 32 of the recess 14 in the handle are straight. For this reason, obviously, means must be provided which prevent the brush head 33 from moving in a direction at right angles to the longitudinal axis of the handle 34. In the case illustrated, this means comprises two lugs 35 on the underface of the back of the brush head, cooperating with two sockets 36 in the bottom 37 of the recess. Both the said lugs 75 and sockets are substantially V-shaped in transverse cross-section to permit convenient disengagement of the said elements. In order to remove the brush head illustrated in Figs. 9 to 11, inclusive, of the drawings from 80 the handle, the said head is forced on the handle transversely of the latter, whereby the lugs on the head are disengaged from the sockets in the recess, thereby permitting the said head to be removed from the handle. 85

As appears from the foregoing, the devices herein described are exceedingly simple in construction and may be readily manufactured on a commercial scale. Whenever a brush head is worn or becomes insanitary it 90 may be easily replaced with a new one. It also appears that the brush heads are readily detachable from and mountable upon the handle of the device, and this feature is essential when it is considered that these brush heads should be sterilized practically after 95 each use.

I am aware of the fact that re-fills for toothbrushes are old and well known. As 100 far as known, these re-fills are kept in position upon the brush handle by special and, in most instances, by complicated fastening means. The devices herein disclosed have the brush head fastening means made integral therewith so that there is nothing to be 105 mislaid or lost, nor to be thrown out of gear.

What I claim is:—

1. A toothbrush comprising a resilient handle having in one of its ends a recess, a brush head fitted into said recess and including a back, the transverse front and rear walls of 110 said recess being undercut and the transverse sides of said back being beveled to snugly fit the undercut walls of said recess, the end wall of said recess being adapted to be disengaged from the adjacent beveled side of said brush back by bending that portion of said handle which is disposed beneath said recess away from said brush back, the transverse front and rear walls of said recess and the beveled sides of said back being substantially 115 V-shaped whereby movement of said brush head transversely of said handle is prevented.

2. A toothbrush comprising a resilient handle having in one of its ends a recess, a brush head fitted into said recess and including a back, the transverse front and rear walls of 120 said recess being undercut and the transverse sides of said back being beveled to snugly fit the undercut walls of said recess, the end wall 125 of said recess being adapted to be disengaged from the adjacent beveled side of said brush back by bending that portion of said handle which is disposed beneath said recess away from said brush back, the transverse front and rear walls of said recess and the beveled sides of said back being substantially 130 V-shaped whereby movement of said brush head transversely of said handle is prevented.

of said recess being adapted to be disengaged from the adjacent beveled side of said brush back by bending that portion of said handle which is disposed beneath said recess away from said brush back, the sides of said handle being provided with notches in alignment with said recess to permit the fingers of the

user to engage said brush back for removing the same from said recess.

Signed at New York, in the county of New ¹⁰ York, and State of New York, this 4th day of May, A. D., 1928.

SAMUEL SPITZ.
